UNITED STATES PATENT OFFICE

SAMUEL P. SHACKLETON, OF WYOMING, NEW JERSEY, ASSIGNOR TO AMERICAN TELEPHONE AND TELEGRAPH COMPANY, A CORPORATION OF NEW YORK

RELAY ARRANGEMENT

Application filed December 17, 1929. Serial No. 414,799.

This invention relates to relay arrangements. It provides means for determining the failure of operation of the contacts associated with the armatures of a relay. It also 5 provides means for indicating the accidental or foreign grounding of the conductors leading to a relay, or other conditions tending to interfere with the proper operation of one or more relays.

10 This invention will be better understood from the detailed description hereinafter following, when read in connection with the accompanying drawing showing one embodiment of the invention merely for the purpose 15 of illustration.

Referring to the drawing, a switch S is shown associated with the plurality of contacts located circularly about the fixed terminal of the switch as a center, the fixed terminal of the switch being grounded. When switch S closes the contact at the extreme right, a relay R₁ is operated, the completed circuit including a battery B₁, the winding of relay R₁, switch S, and ground. It is to 20 be noted that relay R₁ is normally unoperated. Relay R₁ has a plurality of armatures, four of which are shown for the sake of illustration, with each of which a contact is associated. All of the armatures of relay R₁ 25 are grounded in common. It will be apparent that the contact associated with each armature of relay R₁ is normally open and becomes closed only when relay R₁ becomes operated. Thus, when relay R₁ is operated 30 all of its armatures are simultaneously attracted and all of the associated contacts become closed. The contact associated with the second armature from the extreme left will be designated K₁.

40 The armature of relay R₁ associated with contact K₁ controls the operation of a plurality of relays only two of which are shown and are designated R₂ and R'₂. One terminal of each of the windings of relays R₂ and R'₂ 45 respectively, is connected to contact K₁ of relay R₁. The other terminal of each of these windings is connected to batteries B₂ and B'₂ respectively. The features of relay R₂ will be described in somewhat greater detail hereinafter, although it is to be under-

stood that relay R'₂ is similar in all respects to relay R₂ and that other similar relays are also connected to a conductor L₂₀ which is directly connected to contact K₁ of relay R₁. The number of relays similar to the one designated R₂, which may be connected in the manner indicated, is determined in most part by the current carrying capacity of the contact K₁ of relay R₁. 55

When contact K₁ of relay R₁ becomes closed, 60 relay R₂ operates, the completed circuit including battery B₂, the winding of relay R₂, contact K₁ of relay R₁, and its associated armature and ground. Relay R₂ has four armatures all of which are grounded in common. 65 It seems needless to say that when relay R₂ becomes operated, all of its armatures become attracted and close the associated contacts. However, relay R₂ is normally unoperated and the contacts associated 70 with its armatures are normally open.

Each of the contacts of relay R₂ is directly connected to one terminal of each of the windings of a plurality of similar relays. The four armatures of relay R₂, which are 75 shown in the drawing, are directly connected to the windings of relays R₃₀ and R'₃₀; R₃₁ and R'₃₁; R₃₂ and R'₃₂, and R₃₃ and R'₃₃ respectively. Grounded batteries are connected to the other terminal of each of these 80 windings, and these batteries are designated B₃₀ and B'₃₀; B₃₁ and B'₃₁; B₃₂ and B'₃₂; and B₃₃ and B'₃₃ respectively. All of these batteries are preferably of the same potential and are similarly poled, and may, if desired, 85 be replaced by a single battery of sufficiently large capacity.

A relay R₄ is associated with the contacts of relay R₂. Relay R₄ has two similar windings and these are preferably wound in the same direction. The terminals of the upper winding of the relay R₄ are directly connected to the contacts associated with the two armatures at the left of relay R₂ respectively. The terminals of the lower winding of the relay R₄ are similarly connected to the contacts associated with the two armatures at the right of relay R₂. 95

The relay R₄ has two armatures which are 100 normally unoperated, and both of these ar-

matures are grounded. The contact associated with the upper of these armatures is directly connected to a ringer or sounder designated C and a source of alternating current A which is grounded and which transmits current of a frequency suitable to operate the ringer or sounder C. The contact associated with the lower of the armatures of relay R₄ is connected in series with the filament of a lamp F and a battery B₄ which is grounded. It is to be understood that a relay similar to the one designated R₄, and a circuit similar to the one associated with the lower armature of this relay, may be connected to the contacts provided by the armatures of relay R'₂, and with each of the other relays associated with the conductor L₂₀.

In connection with the relay R₁ it may be stated that each of the contacts controlled by each of its armatures terminates in an arrangement similar to the one shown in the drawing above relay R₁, the arrangement including relays R₂ and R'₂, relays R₃₀ to R₃₃ inclusive, relays R'₃₀ and R'₃₃ inclusive, and relay R₄. It may also be stated that each of the conductors L₁₁, L₁₂ and L₁₃, which extend from the contacts of switch S, may be connected to circuits similar to those shown in the drawing and described hereinabove, including a relay such as R₁ and all of its related circuits.

The terminals of the windings of relay R₄ are all directly connected to batteries of the same potential and of the same polarity, each through the winding of a relay such as R₃₀, R₃₁, R₃₂ and R₃₃. If relay R₂ is unoperated, relay R₄ will be unoperated and the contacts associated with the armatures of relay R₄ will be open. When relay R₂ becomes operated, the armatures of relay R₂ will close their associated contacts and ground will then be connected to each terminal of the windings of relay R₄. Under ordinary conditions relay R₄ will remain unoperated. If, however, there is a poor contact at, for example, K₂, the contact associated with the first armature at the left of relay R₂, then the lower terminal of the upper winding of relay R₄ will not be properly grounded and current will flow through this upper winding, causing the relay R₄ to operate. Under these circumstances, current will flow from battery B₃₁ through the winding of relay R₃₁, the upper winding of relay R₄, the armature and contact at the extreme left of relay R₂, and ground. Similarly, current will flow from battery B'₃₁ through the winding of relay R'₃₁ and from any other batteries through corresponding relays associated with the conductor tied to contact K₂. Then both of the armatures of relay R₄ will be simultaneously attracted, closing their associated contacts. The closure of the upper contact will permit current to flow from source A through the ringer or sounder C, causing an audible alarm.

Closure of the lower contact of relay R₄ will permit current to flow from battery B₄ through the lamp F, causing a visual signal. These visual and audible signals will apprise the operator of an unsatisfactory condition which may be traced to a faulty contact at K₂ of relay R₂.

Assuming now that the contacts associated with the various relays of the arrangement shown in the drawing and described hereinabove, are not faulty, and that all of the relays are unoperated, an accidental or foreign ground at one of the conductors associated with the contacts of relay R₂ will cause the alarm circuits associated with relay R₄ to become operated. For the sake of illustration an accidental or foreign ground may be assumed to occur at the point designated G, the grounded condition being shown by dotted lines. The grounded condition at G will cause all of the relays associated with the grounded conductor to become falsely operated. Those relays designated R₃₁ and R'₃₁ will therefore attract their respective armatures, and the upper winding of relay R₄ will become energized due to the flow of current from battery B₃₀ through the winding of relay R³⁰, the upper winding of relay R₄, and the ground designated G. It will be apparent that current will flow from battery B'₃₀ through the winding of relay R'₃₀ and from similar current sources through windings of corresponding relays associated with the conductor tied to the contact at the extreme left of relay R₂. Thus, the device C will be sounded and the lamp F will provide the required visual indication. Similarly the device C will be sounded and the lamp F lit if anyone of the pair of conductors associated with either of the windings of relay R₄ becomes grounded.

While this invention has been shown and described in one particular embodiment merely for the purpose of illustration, it is to be clearly understood that the principles of this invention may be applied to other and widely varied organizations without departing from the spirit of the invention and the scope of the appended claims.

What is claimed is:—

1. The combination of a first relay having two armatures both of which are grounded and two associated contacts, a second relay the winding of which is connected to the two contacts of the first relay, means for applying equal potentials of the same polarity to both terminals of the winding of the second relay, and an alarm circuit controlled by the second relay.

2. The combination of a first relay having four armatures all of which are grounded, a second relay having two windings each connected to the two contacts associated with two of the armatures of the first relay, a source of potential applied in common to

the various terminals of both windings of the second relay, and an alarm circuit controlled by the second relay.

3. A testing system comprising a first relay having four armatures all of which are grounded and four associated contacts, a second relay having two windings the four terminals of which are directly connected respectively to the various contacts of the first relay, a source of direct current potential, four impedance elements connected respectively between the source of direct current potential and the four contacts of the first relay, and an alarm circuit controlled by the second relay.

In testimony whereof, I have signed my name to this specification this 16th day of December, 1929.

SAMUEL P. SHACKLETON.
